(57) **CLAIM**

The ornamental design for a protective cover for a sensor, as shown and described.

DESCRIPTION

1. Protective cover for a sensor
- 1.1 is a top view;
- 1.2 is a rear view;
- 1.3 is a left side view;
- 1.4 is a rear perspective view;
- 1.5 is a front view; and
- 1.6 is a front perspective view.
